UNITED STATES PATENT OFFICE

WILLIAM H. JOY, MARK H. SMITH, AND FRANCIS KORFF, OF LANSING, MICHIGAN,
ASSIGNORS TO KORFF MANUFACTURING COMPANY, OF LANSING, MICHIGAN.

DETACHABLE RUNNER FOR FOLDING GO-CARTS.

1,017,417.

Specification of Letters Patent.

Patented Feb. 13, 1912.

Application filed May 12, 1911. Serial No. 626,739.

To all whom it may concern:

Be it known that we, WILLIAM H. Joy, MARK H. SMITH, and FRANCIS KORFF, citizens of the United States, residing at Lansing, Michigan, have invented certain new and useful Improvements in Detachable Runners for Folding Go-Carts, of which the following is a specification.

This invention relates to improvements in detachable runners for carriages.

Our improved detachable runner is especially designed by us for use on folding go-carts or carriages, of the type in which the wheels fold under the body when the carriage is collapsed, although it is desirable for and adapted for use in various other types.

The main objects of this invention are to provide an improved detachable runner for carriages which can be attached or removed without the use of tools and which is very secure when attached.

Another object is to provide an improved detachable runner for carriages which may be readily adjusted to carriages of different sizes, so that great accuracy in manufacturing is not required.

Further objects, and objects relating to structural details, will definitely appear from the detailed description to follow.

We accomplish the objects of our invention by the devices and means described in the following specification.

The invention is clearly defined and pointed out in the claims.

A structure which is a preferred embodiment of our invention is clearly illustrated in the accompanying drawing, forming a part of this invention, in which—

Figure I is a detail side elevation of a structure embodying the features of our invention, a pair of carriage wheels with their connecting bar being shown in connection therewith to illustrate the manner of applying the runner to the wheels, the locking toggle being shown in its released position by dotted lines. Fig. II is an inside perspective view of our improved detachable runner. Fig. III is an enlarged cross section of the runner taken on a line corresponding to line 3—3 of Fig. II.

In the drawings similar reference characters refer to similar parts throughout the several views.

Referring to the drawings, 1 represents

the front and 2 the rear wheels of a carriage. The wheels are carried by the side bar 3. The structure of the carriage is not further shown herein, as it forms no part of our invention and there are various forms of carriages to which our improved runner may be attached. The runner 4 is formed of angle iron. Seats for the wheels are provided by attaching to the horizontal or shoe portion of the runner the angle plates 5. The runner is curved upwardly at its forward end to form the nose 6. The rear end of the shoe portion of the runner is curved up at 7. The plates 5 co-act with the vertical arm 8 of the runner in forming seats for the wheel as shown.

The runner is clamped and locked upon the wheels by means of an adjustable attaching member for one wheel comprising a link 9 pivoted to the vertical arm 8 of the runner at 10, the link being offset at its outer end 11 to receive the shank of the wheel engaging hook 12. The shank of the hook 12 is threaded and is adjustably secured to the link by means of the nuts 13. A clamping toggle is provided for the other wheel and consists of the link 14 mounted on the pivot 10. A lever 15 is pivoted to the link 14 at 16; and the wheel engaging hook 17 is pivoted to the lever 15 at 18. The hook 17 is adapted to engage the felly of the wheel when the lever 15 is swung up to the position indicated by dotted lines in Fig. I, or as shown in full lines in Fig. II.

To lock the toggle and clamp the wheel, the lever 15 is swung down against the runner as is shown by full lines in Fig. I; this applies tension to the runner and clamps and locks the parts in place. The hook 12 is adjusted to secure the desired clamping tension when the toggle is locked. By thus arranging the parts we secure a structure which may be readily attached or detached, and which, when attached is very secure. Further, it is adjustable so that it may be applied to carts differing quite materially in size, that is, in the space between the wheels, and great accuracy in manufacturing either the carriage or the runners is not required.

Our improved runner when attached is neat in appearance and can be readily attached or detached without the use of tools after the adjustable member has been adjusted to the particular carriage on which the runner is to be used. Where the run-

ner is made especially for a particular go-cart no adjusting device is needed.

We have illustrated and described our improvement in a simple and effective embodiment thereof. We are aware, however, that considerable variation and construction of details are possible, but as such variations will no doubt be obvious to those skilled in the art to which this invention relates, we have not attempted to illustrate or describe the same therein.

Having thus described our invention, what we claim as new and desire to secure by Letters Patent is:

- 15 1. The combination with the front and rear wheels, of a carriage; a runner formed of angle metal adapted to receive said wheels; plates secured to said runner to coact with the vertical arm of the angle metal to form seats to retain the wheels; an adjustable attaching member comprising a link pivoted to said runner between the wheels, an adjustable wheel engaging hook having a threaded shank and lock nut means connected to said link; and a clamping toggle comprising a link pivoted on said runner between the wheels, a lever pivoted on said toggle link, and a wheel engaging hook pivoted on said lever, the pivot for said hook being disposed so that it is carried past the dead center line of the pivots for the lever to the link and for the link to the runner when the lever is forced against the runner, for the purpose specified.
- 20 2. In a runner attachment for a carriage, a runner formed of angle metal adapted to receive the wheels; plates secured to said runner to coact with the vertical arm of the angle metal to form seats to retain the wheels; an adjustable attaching member comprising a link pivoted to said runner between the wheels, an adjustable wheel engaging hook having a threaded shank and lock nut means connected to said link; and a clamping toggle comprising a link pivoted on said runner between the wheels, a lever pivoted on said toggle link, and a wheel engaging hook pivoted on said lever, the pivot for said hook being disposed so that it is carried past the dead center line of the pivots for the lever to the link and for the link to the runner when the lever is forced against the runner, for the purpose specified.
- 25 3. In a runner attachment for a carriage, a runner formed of angle metal adapted to receive the wheels; plates secured to said runner to coact with the vertical arm of the angle metal to form seats to retain the wheels; an adjustable attaching member comprising a link pivoted to said runner between the wheels, an adjustable wheel engaging hook having a threaded shank and lock nut means connected to said link; and a clamping toggle comprising a link pivoted on said runner between the wheels, a lever pivoted on said toggle link, and a wheel engaging hook pivoted on said lever, the pivot for said hook being disposed so that it is carried past the dead center line of the pivots for the lever to the link and for the link to the runner when the lever is forced against the runner, for the purpose specified.
- 30 4. In a runner attachment for a carriage, a runner formed of angle metal adapted to receive the wheels; plates secured to said runner to coact with the vertical arm of the angle metal to form seats to retain the wheels; an adjustable attaching member comprising a link pivoted to said runner between the wheels, an adjustable wheel engaging hook having a threaded shank and lock nut means connected to said link; and a clamping toggle comprising a link pivoted on said runner between the wheels, a lever pivoted on said toggle link, and a wheel engaging hook pivoted on said lever, the pivot for said hook being disposed so that it is carried past the dead center line of the pivots for the lever to the link and for the link to the runner when the lever is forced against the runner, for the purpose specified.
- 35 5. In a runner attachment for a carriage, a runner, with seats to receive the wheels; an adjustable attaching member comprising a link pivoted to said runner between the wheels, an adjustable wheel engaging hook connected on said link; and a clamping toggle comprising a link pivoted on said runner between the wheels, a lever pivoted on said toggle link, and a wheel engaging hook pivoted on said lever, the pivot for said hook being disposed so that it is carried past the dead center line of the pivots for the lever to the link and for the link to the runner when the lever is forced against the runner, for the purpose specified.
- 40 6. In a runner attachment for a carriage, a runner, with seats to receive the wheels; an adjustable attaching member comprising a link pivoted to said runner between the wheels, an adjustable wheel engaging hook connected on said link; and a clamping toggle comprising a link pivoted on said runner between the wheels, a lever pivoted on said toggle link, and a wheel engaging hook pivoted on said lever, the pivot for said hook being disposed so that it is carried past the dead center line of the pivots for the lever to the link and for the link to the runner when the lever is forced against the runner, for the purpose specified.
- 45 7. In a runner attachment for a carriage, a runner formed of an angle metal adapted to receive the wheels; plates secured to said runner to coact with the vertical arm of the angle metal to form seats to retain the wheels; an adjustable attaching member comprising a link pivoted to said runner between the wheels, an adjustable wheel engaging hook connected to said link; and a clamping toggle comprising a link pivoted on said runner between the wheels, a lever pivoted on said toggle link, and a wheel engaging hook pivoted on said lever,

gaging hook pivoted on said lever, the pivot for said hook being disposed so that it is carried past the dead center line of the pivots for the lever to the link and for the link to the runner when the lever is forced against the runner, for the purpose specified.

4. In a runner attachment for a carriage, a runner formed of angle metal adapted to receive the wheels; plates secured to said runner to coact with the vertical arm of the angle metal to form seats to retain the wheels; an attaching member comprising a link pivoted to said runner between the wheels, a wheel engaging hook connected on said link; and a clamping toggle comprising a link pivoted on said runner between the wheels, a lever pivoted on said toggle link, and a wheel engaging hook pivoted on said lever, the pivot for said hook being disposed so that it is carried past the dead center line of the pivots for the lever to the link and for the link to the runner when the lever is forced against the runner, for the purpose specified.

5. In a runner attachment for a carriage, a runner, with seats to receive the wheels; an adjustable attaching member comprising a link pivoted to said runner between the wheels, an adjustable wheel engaging hook connected on said link; and a clamping toggle comprising a link pivoted on said runner between the wheels, a lever pivoted on said toggle link, and a wheel engaging hook pivoted on said lever, the pivot for said hook being disposed so that it is carried past the dead center line of the pivots for the lever to the link and for the link to the runner when the lever is forced against the runner, for the purpose specified.

6. In a runner attachment for a carriage, a runner, with seats to receive the wheels; an attaching member comprising a link pivoted to said runner between the wheels, a wheel engaging hook connected on said link; and a clamping toggle comprising a link pivoted on said runner between the wheels, a lever pivoted on said toggle link, and a wheel engaging hook pivoted on said lever, the pivot for said hook being disposed so that it is carried past the dead center line of the pivots for the lever to the link and for the link to the runner when the lever is forced against the runner, for the purpose specified.

7. In a runner attachment for carriages, a runner provided with seats to receive the wheels; means for attaching said runner comprising a hook member adapted to be engaged with one of said wheels, said hook being connected to said runner between said wheels and provided with adjusting means, and a clamping toggle comprising a link pivoted to said runner between the wheels; a lever connected to said toggle link; and a wheel engaging hook pivoted on said lever,

the pivot for said hook being disposed so that it carries past the center line of the pivots for the lever to the link and for the link to the runner when the lever is forced 5 against the runner, for the purpose specified.

8. In a runner attachment for carriages, a runner; and attaching means comprising a clamping toggle consisting of a link pivoted on said runner, a lever pivoted on said toggle link, and a wheel engaging hook pivoted on said lever, the pivot for said hook being disposed so that it is carried past the center line of the pivots for the lever to the 10 link and for the link to the runner when the lever is forced against the runner.

9. In a runner attachment for a carriage, a runner provided with seats to receive the wheels; attaching means for said runner to 15 said wheels comprising an adjustable member connected to said runner between said wheels; and a toggle connection for said runner to the other wheel, one of the members of the toggle being connected to the runner and the other provided with a wheel 20 engaging member.

10. In a runner attachment for a carriage, a runner provided with seats to receive the wheels; means for attaching said runner to said wheels comprising a connection for the runner to one of the wheels, said connection being mounted on the runner between the wheels; and a clamping toggle connecting the runner to the other 25 wheel, said toggle being connected to the runner between the wheels.

11. A runner attachment for a carriage comprising a runner provided with seats to receive the wheels; means for attaching said 30 runner comprising a hook adapted to en-

gage one of said wheels and having a threaded shank, a member mounted on said runner having a lateral off-set through which said threaded shank is arranged, a nut for said shank, and a coacting connection for said runner to the other wheel, said connection being mounted on the runner between the wheel seats. 45

12. In a runner attachment for a carriage, a runner of angle metal; angle plates 50 arranged with one arm upon and secured to the horizontal arm of the runner, the vertical arm of the angle plates coacting with the vertical arm of the runner to form seats for the wheels, said seat plates being relatively short; and means for attaching the runner to the wheels connected to the runner between said seats, said means being adjustable to locate the runner and to clamp the wheels downwardly on the runner. 55

13. In a runner attachment for carriages, a runner formed of angle metal; angle plates arranged with one arm resting upon and secured to the horizontal arm of said runner, the other coacting with the vertical 60 arm of the runner to form open seats to retain the wheels; and means for attaching said runner to said wheels connected to said runner between said seats and adapted to engage both wheels and clamp the same 65 downwardly upon the runner.

In witness whereof, we have hereunto set our hands and seals in the presence of two witnesses.
